(57) **CLAIM**

The ornamental design for a round sander, as shown and described.

DESCRIPTION

FIG. 1 is a top-down perspective view of a round sander showing my new design;

FIG. 2 is a bottom-up perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partially enlarged view of FIG. 1;

FIG. 10 is a partially enlarged view of FIG. 3;

FIG. 11 is a partially enlarged view of FIG. 4;

FIG. 12 is a partially enlarged view of FIG. 5;

FIG. 13 is a partially enlarged view of FIG. 5;

FIG. 14 is a partially enlarged view of FIG. 6;

FIG. 15 is a partially enlarged view of FIG. 7; and,

FIG. 16 is a partially enlarged view of FIG. 8.

Broken lines depict portions of the round sander that form no part of the claimed design. Dot-dash broken lines depict boundaries of the partially enlarged part of the corresponding figures that form no part of the claimed design.
